UNITED STATES PATENT OFFICE.

HOWARD F. SNYDER, OF NEWTON, IOWA, ASSIGNOR, BY MESNE ASSIGNMENTS, TO THE MAYTAG COMPANY, OF NEWTON, IOWA, A CORPORATION OF DELAWARE.

PACKING AND PACKING DEVICE.

Application filed June 14, 1922. Serial No. 568,157.

The invention relates to packings and packing devices, and more particularly to the type of packings and packing devices adapted for use with oscillating and rotating 5 shafts.

Among the objects of the invention are to provide a new type of packing and packing device adapted for use in washing machines, particularly that having an agitator operated by a shaft extending through the bottom of the tub; to provide a construction wherein the packing surrounds the shaft and is located between the bearings for the shaft; to provide means, preferably in the 10 form of a screw plunger, for applying pressure, from time to time, as may become necessary, to compensate for the loss in packing owing to wear and leakage of the packing through the bearing or bearings; to provide 15 a packing of comminuted asbestos and graphite, with or without oil, so that the packing mass will be in a sort of fluidal state, whereby, when pressure is applied to the mass, as by a screw plunger, the mass 20 will flow about the shaft and into the bearing or bearings and not only lubricate the same but also form a water seal about the shaft and for the bottom of the tub; and such further objects, advantages and capabilities as will hereinafter more fully 25 appear.

My invention further resides in the composition of matter, combination, construction, and arrangement of parts described 30 herein and illustrated in the accompanying drawings, and while I have shown therein a preferred embodiment, I desire the same to be understood as only illustrative of and not as limiting my invention.

40 In the accompanying drawing illustrating my invention:—

Fig. 1 is a vertical sectional view through the packing device and a portion of a washing machine.

45 Fig. 2 is a detail sectional view through the agitator supporting and operating means.

Fig. 3 is a sectional view taken on line 3—3 of Fig. 1.

Referring more in detail to the drawing, 50 the packing device illustrated comprises a chamber 1 forming an integral portion of a plate 2 bolted to, and closing the lower opening of, a tub 3 of a washing machine. An agitator shaft 4 extends vertically through the chamber 1 and is rotatably supported

in bushings 5 and 6 respectively located in bearing hubs 7 and 8 forming integral portions of the plate 2 and a bracket 9 secured, in a suitable manner, to the underside of the plate 2. To the upper end of the shaft 4 60 is fastened a step 10 by means of the cross-pin 11 extending transversely through the shaft 4. The step 10 is of pyramidal form and square in cross section. It extends upwardly above the bottom of the tub 3 and 65 supports an agitator 12 which has a depending hollow socket 13, also square in cross section, to fit upon the step. The step has a lower end portion 14 of cylindrical form which rotatably fits into a circular opening 70 provided in the upper wall of the chamber 1. Against the lower end of the step and surrounding the shaft, as well as fitting in the opening in the upper wall of the chamber 1, is a leather packing washer 15. 75

Upon the shaft 4 between the hubs 7 and 8, is keyed a pinion 16 which is in thrust engagement with the hubs 7 and 8. This pinion is designed to be operated by a reciprocating rack driven by the operating mechanism of the washing machine, in order to give the agitator, through the media of the pinion 16, the shaft 4 and step 10, an angular reciprocation or oscillation within the tub 3. The lower end of the shaft has a grease cup 80 85 17 for supplying a suitable lubricant, to the bearings, in bushings 5 and 6, through the bores 18, 19 and 20 provided in the shaft 4.

The bracket 9 is provided, at one side, with a plunger chamber 21 communicating 90 with the chamber 1 by means of a passage 22 formed integral with the chamber 1. In the lower portion of the bracket 9 is provided a threaded aperture designed to receive a screw plunger 23 into the plunger chamber 95 21. Within the plunger chamber 21, the passage 22, and the chamber 1, is located a packing or packing material 24 composed preferably of asbestos, graphite and oil. The asbestos is cut into fine pieces or shredded so as to provide a comminuted mass. The lower end of the plunger 23 has a finger piece 25 by which the plunger may be manually rotated to apply pressure to the packing material and cause the same to 100 be forced along the passage 22 and into the chamber 1 around the shaft 4, and against the packing washer 15 and the upper wall of the chamber. The packing material is semi-plastic and in a sort of a fluidal state such 110

that when the plunger is operated to stress the mass in the plunger chamber it will cause the packing to flow through the passage 22 and into the chamber 1. In this way any loss of material owing to wear or leakage through the bearings will be compensated for by a simple turn of the plunger screw. In this way leaking of the cleansing or other fluids contained in the tub 3, down wardly through the opening in the upper wall of the chamber, will be prevented.

In addition to the packing material acting as a packing it also acts as a lubricant owing to its oil and graphite constituents. At the same time the bearings in bushings 5 and 6 will be maintained lubricated by the lubricating ingredients contained in the packing material.

It is of course understood that the specific description of structure and composition of matter set forth above may be departed from without departing from the spirit of my invention as set forth in this specification and the appended claims.

Having now described my invention, I claim:

1. A shaft packing and lubricating device for washing machines comprising bearings for said shaft, a packing chamber surrounding said shaft, said chamber having side walls connected to the bottom portion of a washing machine and making a tight closure to prevent any leakage from said machine, a plunger chamber eccentrically located with respect to said shaft, a passage extending from said plunger chamber and extending to said packing chamber, a fluidal packing in said chambers and passage, and a vertically disposed screw plunger located in said eccentrically disposed plunger chamber and operable to compensate for loss and to lubricate said bearings.

2. A shaft packing and lubricating device for washing machines comprising bearings for said shaft, a packing chamber surrounding said shaft, said chamber having side walls connected to the bottom portion of a washing machine and making a tight closure to prevent any leakage from said machine,

50 a plunger chamber eccentrically located with respect to said shaft, a passage extending from said plunger chamber and extending to said passage chamber, a fluidal packing in

said chambers and passage, and means in said eccentrically disposed plunger chamber 55 operable to compensate for loss and to lubricate said bearings.

3. A shaft packing and lubricating device for washing machines, comprising a combined plate and bracket secured to the bottom of a washing machine and preventing leakage therefrom, bearings secured in said bracket member, a packing chamber surrounding said shaft, a plunger chamber eccentrically located with respect to said shaft, 60 a passage extending from said plunger chamber and extending to said packing chamber, a fluidal packing in said chambers and passage, and a vertically disposed screw plunger located in said eccentrically disposed 65 plunger chamber and operable to compensate for loss and lubricate said bearings.

4. A shaft packing and lubricating device for washing machines, comprising a combined plate and bracket secured to the bottom of a washing machine and preventing leakage therefrom, bearings secured in said bracket member, a packing chamber surrounding said shaft, a plunger chamber eccentrically located with respect to said shaft, 75 a passage extending from said plunger chamber and extending to said packing chamber, a fluidal packing in said chambers and passage, and means in said eccentrically disposed plunger chamber and operable to compensate for loss and to lubricate 80 said bearings.

5. A shaft packing and lubricating device for washing machines, comprising a combined plate and bracket secured to the bottom of a washing machine and preventing leakage therefrom, bearings secured in said bracket member, a packing chamber located above said bearings and surrounding said shaft, a plunger chamber eccentrically located with respect to said shaft, a passage extending from said plunger chamber and extending to said packing chamber, 90 a fluidal packing in said chambers and passage, and means in said plunger chamber 95 operable to compensate for loss and to lubricate said bearings.

In witness whereof I hereunto subscribe my name to this specification.

HOWARD F. SNYDER.
